UNITED STATES PATENT OFFICE.

HARRY ULMER, OF PHILADELPHIA, PENNSYLVANIA, ASSIGNOR TO HARDWICK & MAGEE CO., OF PHILADELPHIA, PENNSYLVANIA, A CORPORATION OF PENNSYLVANIA.

DESIGN FOR A RUG.

50,800.

Specification for Design.

Patented May 15, 1917.

Application filed March 24, 1917. Serial No. 157,280. Term of patent 3½ years.

To all whom it may concern:

Be it known that I, HARRY ULMER, a citizen of the United States, residing in Philadelphia, Pennsylvania, have invented a certain new, original, and ornamental Design for a Rug, of which the following is a specification, reference being had to the accompanying drawing, forming part thereof, in which the figure is a plan view of a portion of a rug forming the subject of my new, original, and ornamental design.

I claim:—

The ornamental design for a rug, substantially as shown.

In witness whereof I affix my signature.

HARRY ULMER.
